Des. 213,163
Patented Jan. 7, 1969

213,163

MOTORCYCLE HANDLEBAR

Frank G. Stone, Los Angeles County, Calif., assignor of one-half to Peter Mead, Canoga Park, Calif.

Filed Apr. 3, 1968, Ser. No. 11,280

Term of patent 14 years

U.S. Cl. D90—11
Int. Cl. D12—14

I claim:

The ornamental design for a motorcycle handlebar, substantially as shown and described.
